S. McFARLAND

RAIL JOINT

Filed May 18, 1921

FIG. I.

FIG. II.

FIG. III.

INVENTOR:

SAMUEL McFARLAND,

*J. William C. Page,
Atty.*

UNITED STATES PATENT OFFICE.

SAMUEL McFARLAND, OF COATESVILLE, PENNSYLVANIA.

RAIL JOINT.

Application filed May 18, 1921. Serial No. 470,730.

To all whom it may concern:

Be it known that I, SAMUEL McFARLAND, a citizen of the United States, residing at Coatesville, in the county of Chester and 5 State of Pennsylvania, have invented a certain new and useful improvement in Rail Joints, whereof the following is a specification, reference being had to the accompanying drawing.

10 Ordinary rail joints are of two distinct classes; first, including what are termed "fish plates" and "angle plates," which both support the rails by engagement under the flanges of the rail heads; second, what are 15 termed "bridge plates", which support the rails under their bases, and not under their heads. It is the object and effect of my invention to combine the advantages of both those classes in a single structure which I 20 term a "fish bridge plate" and which operates to support the rails by engagement not only beneath their heads but beneath their bases. It is characteristic of the ordinary fish plates that bolt holes must be made 25 through the vertical webs of the rails to connect such plates therewith. On the contrary, my improved joint does not require any holes to be made through the rails. Moreover, as ordinary bridge plates require 30 bolts to secure the rail base flanges to them; it may be observed that my invention is advantageous in that no bolts are required to form a joint in accordance therewith.

As hereinafter described, my invention 35 includes a single, unitary, fish bridge plate, which may be made of cast or wrought metal, and which bridges the space between adjoining railway ties and supports adjoining ends of two rails which are alined and 40 abutted therein; such support being afforded by a web extending horizontally in said bridge plate, and throughout the length thereof, beneath the bases of said rails, and by angle fish flanges which extend, in unitary relation with that web, upwardly into engagement with both the upper surfaces of the rail base flanges and the lower surfaces of the rail heads. Said bridge plate has, intermediate of its length, a socket extending 45 vertically through it for a removable plug in which the abutting ends of said rails are tightly fitted; so that, if and when the joint becomes worn at that point, it 50 may be renewed by simply substituting a new plug for the old one.

My invention includes the various novel features of construction and arrangement hereinafter more definitely specified.

In said drawing; Fig. I is a perspective view of a rail joint embodying my invention.

Fig. II is a detached perspective view, on a larger scale, of the central plug indicated in Fig. I.

Fig. III is a central transverse sectional view, on a larger scale, of the joint shown in Fig. I.

In said figures; the fish bridge plate 1 is a single unitary piece of cast or forged metal having the plane web 2 extending 65 horizontally beneath the base flanges 3 of the rails 5 and 6 from end to end of said plate 1.

Said web 2 has oppositely counterpart angle fish flanges 8 extending upwardly 75 therefrom with angle base members 9 bearing upon the upper surfaces of said rail base flanges 3. The vertical members of said flanges 8 are recessed at 10, in spaced relation with the side surfaces of the vertical webs 11 of said rails 5 and 6, and have flanges 12, at their upper edges, precisely fitting the under surfaces of the rail heads 13; whereby said rails 5 and 6 are supported 80 throughout their length in said plate 1 not only at their bases but at their heads.

Of course, said rails 5 and 6 have the greatest tendency to move vertically at their abutted ends, intermediate of the length of said plate 1. Consequently, the rail joint is 90 subjected to the greatest wear at that point, incident to the vibration of the rail ends. Therefore, in order to prolong the life of the joint, as a whole; I prefer to embody my invention in a structure which is susceptible of partial renewal at that region of greatest wear. In the form shown; the fish bridge plate 1 is provided with the central vertical cylindrical socket 15 which is wider than the rail base flanges 3 and affords a seat 16 for the removable cylindrical plug 17 which has the slot 18 extending transversely therethrough, precisely fitted to the configuration of the rails, as shown in Fig. III. In order to tightly fit said removable plug 17 in said plate 1 so as to be in rigid relation with the latter; I provide said plug with the cylindrical shank 20 which is adapted to fit in the reduced cylindrical lower portion 21 of said socket 105 110

15, as shown in Fig. III. Said shank 20 is provided with opposite radially extending lugs 23 which, when in the assembled position shown in Fig. III, extend transversely with respect to the length of said fish bridge plate 1 and tightly fit against the bottom thereof. In order to get said plug into and out of the assembled position shown in Fig. III; I provide said plate 1 with two radially opposite channels 25, large enough to permit the vertical passage of said plug lugs 23, when said plug 17 is turned at right angles to the position shown in Fig. III.

15 That is to say; each fish bridge plate, of the construction and arrangement above described, is primarily fitted with a removable plug 17, by thrusting the latter downwardly, with its radially projecting lugs 23 extending in the direction of the length of said plate 1, so as to register with and pass down the opposite channels 25 in said plate, until the larger upper portion of said plug rests upon said seat 16. Of course, in that position, said slot 18 in the plug extends transversely to the length of said plate 1. Thereupon, said plug is turned, through an arc of ninety degrees, to bring said slot 18 therein in alinement with the passageway between said fish flanges 8; so that each of said rails 5 and 6 may be driven, at one operation, between said flanges 8 and into said slot 18.

Of course, when said plug 17 is thus engaged with the rails, it is impossible to turn it to the position in which it may be withdrawn. However, when it is desired to renew or replace said plug 17, said rails may be disengaged therefrom and said plug 40 turned with its slot 18 again extending transversely to said plate 1, and its lugs 23 in registry with said channels 25, so that it may be driven upwardly in and out of said plate.

45 It is to be particularly noted that such removal and insertion of successive plugs 17 may be effected, and, in fact, the entire joint structure be removed and replaced, without material disturbance of the track of which 50 said rails 5 and 6 are members; by loosening said rails from the ties 27, sliding the plate 1 lengthwise until one of said rails is free from it, then springing the rails apart transversely, so that said plate 1 may be slid 55 lengthwise in the opposite direction until the plug 17 is disengaged from the rails or the entire plate is disengaged from the rails, whichever it is desired to replace. Such replacement can be effected by reversal of 60 manipulation of the rails above described.

Of course, the joint above described is subjected to the greatest stresses intermediate of its length. Therefore, I prefer to provide the plate 1 with a central reinforcement 28 which extends below the bottom of

said web 2, as indicated in Fig. III, and is pendent between the adjoining ties 27, as indicated in Fig. I. The form of the fish bridge plate 1 which I have chosen for illustration is designed to be manufactured of 70 cast metal and, consequently, its cross section in the plane of the junction of the abutting ends of the rails 5 and 6 is more massive than is necessary in a fish bridge plate formed of wrought metal. 75

Although fish bridge plates embodying the features of my invention above described may be directly connected with ties 27 by ordinary spikes 30 having their heads engaging only the angle flanges 9 of the plate 1; I prefer to provide fish bridge plates with flanges 31 which, as best indicated in Fig. III, extend in the same plane as the base web 2 and, as indicated in Fig. I, are provided with notches 32 which are so spaced and proportioned as to fit said spikes 30 and thus anchor the joint against the tendency to creep under the stresses to which all rail joints are subjected by traffic upon the rails. 90

It may be observed that the embodiment of my invention chosen for illustration is adapted to receive but one of the many standard types and sizes of rails. However, it is to be understood that my invention 95 may be adapted to cooperate with rails of any desired configuration.

Therefore, I do not desire to limit myself to the precise details of construction and arrangement herein set forth, as it is obvious that various modifications may be made therein, without departing from the essential features of my invention, as defined in the appended claims. 100

I claim:

1. A rail joint comprising an integral body having a base plate spanning two ties, side flanges fitting the fishing spaces of the rails, and a socket extending vertically through said plate, intermediate of its length, larger at its upper portion than at its lower portion and forming a seat; said plate having flanges provided with spike receiving notches; a removable plug fitted in said socket, having an upper larger portion fitted to rest upon said seat, and a lower smaller portion fitted to extend through the smaller lower portion of said socket; said plug having a transverse rail slot through its larger portion, adapted to receive the rail ends, and having projecting means arranged to extend transversely with respect to said plate, below the bottom thereof and in engagement therewith to prevent the removal of said plug, when the latter is turned with its slot in alinement with said rail ends. 110

2. A rail joint comprising an integral body having a base plate spanning two ties, side flanges fitting the fishing spaces of the rails, 130

and a socket extending vertically through said plate, intermediate of its length, larger at its upper portion than at its lower portion and forming a seat; a removable plug fitted in said socket, having an upper larger portion fitted to rest upon said seat, and a lower smaller portion fitted to extend through the smaller lower portion of said socket; said plug having a transverse rail slot through its larger portion, adapted to receive the rail ends, and having projecting means arranged to extend transversely with respect to said plate, below the bottom thereof and in engagement therewith to prevent the removal of said plug, when the latter is turned with its slot in alinement with said rail ends.

3. A rail joint comprising an integral body having a base plate spanning two ties, side flanges fitting the fishing spaces of the rails, and having, intermediate of its length, a socket forming a seat; a removable plug fitted in said socket, to rest upon said seat; said plug having a transverse rail slot through it adapted to receive the rail ends;

and means arranged to prevent the removal of said plug, when the latter is turned with its slot in alinement with said rail ends.

4. A rail joint comprising an integral body having a base plate spanning two ties; side flanges fitting the fishing spaces of the rails, a socket, and a removable wearing member, fitted in said socket, and comprising parts extending in said fishing spaces and fitting beneath both rail heads at their junction, in position to support said heads. 30

5. A rail joint comprising an integral body having a base plate spanning two ties, side flanges fitting the fishing spaces of the rails, a circular socket at the junction of the rails, and a rotary removable wearing member fitted in said socket. 35 40

In testimony whereof, I have hereunto signed my name at Coatesville, Pennsylvania, this fourteenth day of May, 1921.

SAMUEL McFARLAND.
